UNITED STATES PATENT OFFICE

JOSEPH BETHENOD, OF PARIS, FRANCE

METHOD FOR IGNITION ON COMBUSTION ENGINES

Application filed March 28, 1928, Serial No. 265,443, and in France April 1, 1927.

This invention relates to a new method for ignition on combustion engines. The method consists, substantially, in supplying the ignition plug with the discharge of a condenser 5 permanently associated with the said plug, the said condenser being charged to a voltage not sufficient for striking the spark; the striking of the spark is secured at the proper time by an auxiliary high tension discharge which 10 produces through the space between the plug electrodes a spark, called the pilot spark, which is sufficient to produce the ionization of the spark gap. This said auxiliary spark is itself obtained by means of a magneto, or by 15 an induction coil with a distributor mechanically driven by the engine, or by any other equivalent means. The necessary power for producing the pilot spark being in fact comparatively small, it is easy to understand that 20 the device which has been described, allows the maintenance of an extremely powerful ignition, without requiring the interrupting device, which controls the times of ignition, to handle a large amount of energy.

25 The invention will be well understood by reference to the accompanying drawings, which give as examples, some forms of construction:

Figure 1 shows diagrammatically one circuit arrangement for an ignition system embodying my invention and Fig. 2 illustrates a modified circuit arrangement of an ignition system embodying my invention.

Referring to Fig. 1, 1 is a condenser permanently associated with the ignition plug. The ignition plug is shown diagrammatically at 2. 3 is the common ground for all of the installation. Condenser 1 is charged by the source 4. The source 4 is for example, a direct-current dynamo with a comparatively high voltage. A convenient impedance 5 is inserted, if desired, in the load circuit so as to limit more particularly the source output when condenser 1 is discharging through the plug 2.

45 In order to produce that discharge at the proper time, an auxiliary spark gap is placed in series with a high voltage condenser 7, and the terminals of this assembly are connected to the plug terminals. Condenser 7 is supplied, for example, by the secondary circuit

of a high-tension magneto 8 of a usual type, synchronously driven, as is usual, by the combustion engine. At the time of breaking of the primary circuit of magneto 8, the condenser 7 is suddenly charged, and it immediately discharges through the spark gap 6.

A portion of the discharge flows through the space between the electrodes of the plug 2, and then produces, according to my invention, the discharge of condenser 1. In order 60 to avoid the possibility that the other portion of the initial discharge of condenser 7, which flows through condenser 1, may become too great, I insert if desired, at 12 a reactance coil of suitable reactance. It is to be 65 observed that in case the voltage of the source 4 is, for example, several hundred volts, the capacity 1 will be much larger than the capacity 7; if desired, the capacity 1 will be an electrolytic condenser, or a colloidal one. Of 70 course, magneto 8 can be replaced by an induction coil with a mechanically driven distributor the primary of the coil being supplied by a storage battery or the like.

Referring to Fig. 2, the condenser 7 is also 75 charged by means of a high-tension magneto or the like, but in this case that condenser is a part with the spark gap 6, of an oscillating circuit including a coil 9. This latter is coupled through its mutual inductance with a 80 coil 10, which is inserted between condenser 1 and plug 2. Furthermore it is desirable that the condenser 11, having a much smaller capacity than the condenser 1, be connected to the terminals of the plug.

85 Of course the scheme of Figure 2 can have many other forms of realization. Especially if desired the combination 7, 6, 9, can be replaced by a high-tension source of any other type; for example, it is possible to use a 90 triode tube generator of the type well known in radio. The spark control for the plug can then be made by means of a single rotating switch, synchronously driven by the combustion engine, and preferably operating upon the grid circuit of the triode tube. This switch is then called upon to handle a very small amount of energy, the intensity of the current which flows through it being practically zero.

Of course, all these modes of realization can be easily used in the case of engines having more than one cylinder, by means of adding a high-tension distributor, or the like.

5 What I claim as new and desire to secure by Letters Patent of the United States is as follows:

1. In an ignition system for combustion engines, in combination, a plug, a condenser 10 permanently associated with said plug, a power supply having a high internal impedance for charging said condenser at a voltage lower than the disrupting voltage of the plug, and means including an independent source of current for starting the discharge between the electrodes of the said plug.
2. In an ignition system for combustion engines, in combination a plug, a condenser 20 permanently associated with said plug, a power supply having a high internal impedance for charging said condenser at a voltage lower than the disrupting voltage of the plug, and an auxiliary oscillating circuit 25 supplied at high voltage from an independent current source for starting the discharge between the electrodes of the said plug.
3. In an ignition system for combustion engines, in combination a plug, a condenser 30 permanently associated with said plug, a power supply having a high internal impedance for charging said condenser at a voltage lower than the disrupting voltage of the plug, and an auxiliary oscillating circuit 35 supplied at high voltage from an independent current source and electrically connected to the plug circuit.
4. In an ignition system for combustion engines, in combination a plug, a condenser 40 permanently associated with said plug, a power supply having a high internal impedance for charging said condenser at a voltage lower than the disrupting voltage of the plug, a primary auxiliary oscillating circuit 45 supplied at high voltage from an independent source and indirectly coupled with the plug circuit, and a secondary oscillating circuit electrically connected to the plug circuit and including the said condenser charged 50 from the main power supply, and another condenser shunting the plug and having a capacity which is very much smaller than the capacity of the said condenser charged from the main power supply.

55 JOSEPH BETHENOD.
